UNITED STATES PATENT OFFICE.

HOMER E. FROST, OF CLEVELAND, OHIO, ASSIGNOR TO THE ELECTRIC CONTROLLER & MANUFACTURING COMPANY, OF CLEVELAND, OHIO, A CORPORATION OF OHIO.

ELECTROMAGNETIC DEVICE.

Application filed July 9, 1920. Serial No. 395,021.

To all whom it may concern:

Be it known that I, HOMER E. FROST, a citizen of the United States, residing at Cleveland, in the county of Cuyahoga and

5 State of Ohio, have invented new and useful Improvements in Electromagnetic Devices, of which the following is a specification.

10 My invention relates to electromagnetic devices. I have illustrated it in connection with an electromagnetic switch for alternating current, but it may be applied in other devices.

15 Electromagnets in alternating current circuits frequently retain an objectionable amount of magnetism or fail to release their armatures when the current which energizes the magnet windings is interrupted. It is the object of this invention to provide 20 a means whereby such magnets will promptly discharge their magnetism or release their armatures when the energizing current is cut off.

25 The accompanying drawing shows diagrammatically the application of my invention to an electromagnetic switch.

On the drawing, 1 and 2 designate two supply wires connecting a source of alternating current to the terminals 3 and 4 of the switch 5. The blades 6 and 7 of the 30 switch connect the supply wire to, or disconnect them from, the wires 8 and 9 which are connected to the opposite ends of the operating coil 10 of the electromagnetic switch S. The winding 10 is provided with 35 the armature 11, shown in the present instance as a core. The armature is pivoted to the switch arm 12 by the pin 13, the said arm being pivoted on the pin 14. 15 is the fixed contact of the switch, and 16 is the 40 movable contact which is carried by the

switch arm 12. 17 and 18 are wires leading from the respective contacts 15 and 16 to any suitable translating device.

19 is a resistance connected to the wires 8 and 9 and in parallel with the winding 10. 45 With the resistance 19 the magnet S will release its armature without sticking. In one installation where 900 volts were used with the resistance connected in parallel with the winding of an electromagnetic switch, the 50 armature was released promptly upon the opening of the switch 5; but when the resistance 19 was disconnected from the circuit, the armature stuck at 500 volts or more.

I claim:—

55 1. In an electromagnetic device, an alternating current electromagnet having a magnetic armature, and a resistance connected in parallel with the energizing winding of the magnet to prevent the armature from sticking upon the cessation of the current in the winding. 60

65 2. In an electromagnetic device, an alternating current electromagnet having an open magnetic circuit and a magnetic armature, and a resistance connected in parallel with the energizing winding of the magnet to prevent the armature from sticking upon the cessation of the current in the winding.

70 3. In an electromagnetic device, an alternating current electromagnet having a movable magnetic circuit and a magnetic armature, and a resistance connected in parallel with the energizing winding of the magnet to prevent the armature from sticking upon the cessation of the current in the winding.

75 Signed at Cleveland, Ohio, this 30 day of June, 1920.

HOMER E. FROST.
